UNITED STATES PATENT OFFICE.

FOIST HATMAKER, OF ITHACA, NEW YORK.

REAMER.

SPECIFICATION forming part of Letters Patent No. 530,841, dated December 11, 1894.

Application filed July 13, 1894. Serial No. 517,441. (No model.)

To all whom it may concern:

Be it known that I, FOIST HATMAKER, of Ithaca, in the county of Tompkins and State of New York, have invented a new and Improved Reamer, of which the following is a full, clear, and exact description.

The object of the invention is to provide a new and improved reamer, which is comparatively simple and durable in construction, and more especially designed for the use of plumbers, to conveniently and quickly repair all sizes of faucets and other similar articles.

The invention consists of a hollow handle adapted to carry a reversible shank formed at one end with a fixed cutter head and adapted to support at its other end a reamer with adjustable cutters.

The invention also consists of certain parts and details and combinations of the same, as will be fully described hereinafter and then pointed out in the claims.

Reference is to be had to the accompanying drawings, forming a part of this specification, in which similar letters of reference indicate corresponding parts in all the figures.

Figure 1 is a side elevation of the improvement. Fig. 2 is a longitudinal section of the same. Fig. 3 is a side elevation of the adjustable reamer with the sleeve removed. Fig. 4 is a side elevation of the fixed reamer. Fig. 5 is a side elevation of the sleeve with part in section. Fig. 6 is an enlarged end view of the adjustable reamer; and Fig. 7 is a transverse section of the same on the line 7—7 of Fig. 3.

The improved reamer is provided with a hollow handle A, formed at its open end with an integral screw thread A', adapted to be engaged by the screw threads B' and B² formed on one end of the reamer shank B, the said shank being provided with integral cutters C, as is plainly shown in Figs. 2 and 4.

The threads B' and B² are separated from each other by an integral collar B³, and in this end of the shank B is formed an internal screw thread B⁴ adapted to be engaged by the threaded end D' of a reamer D provided with adjustable cutters, as hereinafter more fully described. The threaded end D' is formed with a reduced portion D², formed with a recess D² adapted to be engaged by a screw E screwing in the collar B³, and adapted

to lock the reamer D in place on the shank B carrying the fixed cutters C. The reamer D is provided with cutters D⁴ having their shanks D⁵ extending longitudinally in grooves D⁶, formed in the smooth end of the reamer shank, the ends of the said cutters being held in place by suitable set screws D⁷ which, however, permit of opening and closing the said cutters to adjust the reamer to any desired size. A screw D⁸ screwing in the end of the reamer shank, moves with its conical head in contact with the beveled edges of the cutter heads D⁴, so that the latter can press outward in contact with a sleeve F screwing on the threaded end D' of the reamer D. The outer end of this sleeve F, is formed with an internal bevel F', against which is adapted to press the outer beveled edges of the cutters D⁴, whenever the operator screws up the screw D⁸. The large reamer H is adapted to be slipped over the cutters D⁴ and sleeve F and is fastened on the latter by a set screw H', as indicated in Figs. 1 and 2, so that the tool may be used for reaming very large sized faucets or other articles.

A cone shaped centering guide G is fitted loosely over the sleeve F, and is adapted to screw on the thread B² of the shank B, as illustrated in Figs. 1 and 2, the centering guide fitting into the aperture of the faucet to center the cutter and to permit of the operator conveniently turning the tool in a central position, to properly ream the desired opening. When it is desired to use the smallest sized reamer C, then the guide G, as well as the reamer D, are removed from the end of the shank B, and the latter is screwed out of the thread B' and reversed, so as to screw with the thread B² into the thread A' of the handle.

The reamer C, extends outward, and the operator in taking hold of the handle A, can ream an article with the reamer C, by turning the handle A. When it is desired to ream openings larger than the size of the reamer C, I employ the adjustable reamer D, by screwing the shank B into the handle A, as illustrated in Fig. 2, and then fasten the threaded end D' in the shank B by the set screw E, and then adjust the set screw D⁸ until the cutters D⁴ measure the proper

size for the opening to be reamed. The operator then turns the handle A, so as to cause the cutters D⁴ to cut and ream the opening. For use in larger openings the reamer H is 5 employed, fastened on the sleeve F, as previously described.

The set screw D⁸ is not to be disturbed after the shank is put together, unless the cutting heads need renewing or repairing.

10 Thus it will be seen that with a reamer of the construction described, the plumber or other mechanic is enabled to conveniently and quickly repair all sizes of faucets, bibs and other articles.

15 Having thus fully described my invention, I claim as new and desire to secure by Letters Patent—

1. A reamer, comprising a hollow handle, a reversible shank adapted to be fastened to 20 the said handle and carrying a fixed reamer, and a reamer having adjustable cutters adapted to be fastened on the said shank, substantially as shown and described.

2. A reamer, comprising a shank, cutters 25 held longitudinally on the said shank, adapted to be bent inward or outward, a sleeve held on the said shank and extending over the said cutters, and a screw screwing in the

shank and engaging the said cutters to press the latter outward into a bent position against 30 the said sleeve, substantially as shown and described.

3. A reamer, comprising a hollow handle, a shank formed with a fixed reamer, and provided with two sets of screw threads adapted 35 to screw in the open end of the said handle, a reamer with adjustable cutters adapted to be fastened in the said shank, and a centering guide adapted to screw on one of the threads on the said shank, substantially as 40 shown and described.

4. A reamer, comprising a hollow handle, a shank formed with a fixed reamer and provided with two sets of screw threads adapted to screw in the open ends of the said handle, 45 a reamer with adjustable cutters adapted to be fastened in the said shank, a centering guide adapted to screw on one of the threads of the shank, and a large cutter adapted to be fastened on the said reamer having adjustable cutters, substantially as shown and described.

FOIST HATMAKER.
